UNITED STATES PATENT OFFICE.

WUI KONG UN, OF HONGKONG, CHINA.

TOY WAR-TANK.

1,315,057

Specification of Letters Patent. Patented Sept. 2, 1919.

Application filed January 14, 1919. Serial No. 271,069.

To all whom it may concern:

Be it known that I, WUI K. UN, a citizen of the Republic of China, residing at Hong-kong, in China, have invented certain new and useful Improvements in Toy War-Tanks; and I do hereby declare the following to be a full, clear, and exact description of the invention, such as will enable others skilled in the art to which it appertains to make and use the same.

This invention relates to toys, and the primary object of the invention is to provide a toy so constructed as to simulate the appearance of a tank.

15 Another object of the invention is to provide a toy war tank having means for propelling the same over the ground, and novel means for controlling the direction of travel of the tank.

20 A further object of the invention is to provide improved means for constructing the tank so that a simple and efficient construction is provided which can be manufactured and placed upon the market at a low cost.

25 With these and other objects in view, the invention consists in the novel construction, arrangement and formation of parts as will be hereinafter more specifically described, claimed and illustrated in the accompanying drawings, forming a part thereof, in which:

Figure 1 is a side elevation of the improved tank,

35 Fig. 2 is a rear elevation of the same,

Fig. 3 is a bottom plan view of the tank partly in section,

Fig. 4 is a vertical longitudinal section through the improved tank, and

40 Fig. 5 is a detail cross section taken on the line 5—5 of Fig. 4.

Referring to the drawings in detail, wherein similar reference characters designate corresponding parts throughout the several views, the numeral 1 generally indicates the improved toy tank which includes side walls 2 and 3 which are preferably formed from a single sheet of material and shaped so as to simulate the appearance of a real tank. The upper side edges of the side walls 2 and 3 are provided with integral inwardly extending right angular flanges, 4 and 5 which are preferably crimped as at 6 to give the appearance of the tractor chains used to propel a real tank over the ground.

A top wall 7, which is preferably formed from a single sheet of material, is secured to the side walls 2 and 3 in any preferred manner, such as by soldering the parts together, and is positioned slightly below the top edge of the side walls. The top wall 7 has its ends bent downwardly as at 8 and 9 to form the usual sloping sides of the tank and the front portion 9 is bent downwardly as at 10 and then inwardly as at 11. The rear portion 8 is bent downwardly as at 12 and then forwardly as at 13 and then downwardly at right angles as at 14, which effectively gives the appearance of the rear portion of a tank. The downwardly inclined portion 12 is provided with an aperture 15 through which protrudes a toy gun 16, which is secured to the wall in any preferred manner. The side walls 2 and 3 are provided with turrets 17 which are formed preferably from a single sheet of metal and soldered to the outer faces of the side walls. The turrets are provided with apertures 18 through which toy guns 19 protrude. These guns are secured to the turrets in any preferred manner.

The tank is to be painted or printed to simulate the appearance of a real tank and vertical lines 20 are to be painted on the sides 2 and 3 so as to give the appearance to the sides as if the same were constructed of plates and a plurality of black dots 21 are placed around the edges of the sides and around the vertical lines so as to give the appearance of rivets extending through the tank. The end and upper walls of the tank are painted in the same manner. The turrets are also painted in this manner and may be further painted so as to give the appearance of real turrets. If so desired, the tank may be simply painted so as to give the effect of having turrets and guns instead of having the outstanding turrets 17 and guns 16 and 19, as shown in the drawings.

An axle 22 has the terminals thereof journaled in the side walls 2 and 3 adjacent the rear end thereof and have keyed or otherwise secured thereto the supporting wheels 23 and 24 which protrude slightly below the lower edge of the side walls. The wheel 24 has secured thereto a relatively small gear wheel 25, which meshes with a relatively large gear wheel 26 which is carried by shaft 27 which has its terminals journaled in the side walls 2 and 3. The relatively large wheel 26 has secured thereto a

relatively small gear 28 which meshes with a relatively large gear 29 carried by the drum 30 which is carried by a shaft 31, the terminals of which are journaled in the side walls 2 and 3. One end of the shaft 31 projects beyond one of the side walls and has secured thereto a key or handle 32, by means of which the drum may be rotated so as to wind the spring 33 which is coiled around the drum. One terminal of this spring is secured to the drum as at 34 and the opposite terminal is secured to the side walls 2 as at 35. A pivoted pawl 36 is arranged to engage the teeth of the relatively large gear 29, so as to hold the same against movement under the influence of the coil spring 33, when the spring has been wound up. A suitable handle 37 is secured to the pawl, so that the same can be lifted out of engagement with the teeth of the large gear wheel 29, so that the same may be rotated by means of the spring 33, when so desired. While the above described mechanism will give the desired results, it is to be understood that any suitable clock work mechanism may be substituted therefor if so desired.

A transverse bracing strip 38 extends across the tank and has its terminals secured to the side walls 2 and 3 in any preferred manner. The strip 38 and the upper wall 7 are provided with aligned openings which rotatably receive a vertical shaft 39, the lower end of which carries an inverted U-shaped yoke 40, the terminals of which are provided with aligned openings which receive a relatively short axle 41 upon which is mounted steering wheel 42. The upper end of vertical shaft 39 is bent at right angles to provide a handle 43 which is positioned above the upper surface of the top wall 7 and forms means whereby the steering wheel 42 may be turned so as to control the direction of travel of the tank.

From the foregoing description, it can be seen that an improved toy has been provided, which is so constructed as to simulate the appearance of a tank. While the device has been described as being made of sheet

metal, it is to be understood that the same 50 may be constructed of any material that may be desired.

In practice, I have found that the form of my invention illustrated in the accompanying drawings and referred to in the above 55 description, as the preferred embodiment, is the most efficient and practical; yet realizing the conditions concurrent with the adoption of my device will necessarily vary, I desire to emphasize that various minor 60 changes in details of construction, proportion and arrangement of parts may be resorted to, when required without sacrificing any of the advantages of my invention as set forth. 65

What I claim as new is:

1. A figure toy comprising substantially parallelogram side walls, the upper and side edges of the side walls being provided with inwardly extending right angular directed 70 flanges, said flanges being crimped, an upper wall connecting the side walls and positioned below the flanges, the upper wall being provided with inclined front and rear extensions to form front and rear walls of 75 the toy, and means to propel the toy over the ground.

2. A toy tank comprising parallelogram side walls, the upper and side edges of the walls being bent inwardly at right angles to 80 provide flanges, the flanges being crimped, an upper wall connecting the side walls and positioned below the flanges, front and rear extensions formed on the upper wall, an axle carried by the side walls adjacent the rear 85 ends thereof, wheels secured to the axles, a spring drum, means for winding the spring drum, a train of gears operatively connecting the spring drum with the axle, and a steering wheel carried by the forward portion of the toy. 90

In testimony whereof I affix my signature in presence of two witnesses:

WUI KONG UN.
